W. Easby.

Coffer Dam.

Patented Nov. 19, 1833.

William Eastby 1794 Nov 19, 1833

Nov 19, 1833

The Subscule referred to in these letters Patent and enclosing part of the same containing a description in the words of the said William Eastby himself of his improvement in the construction of Coffre Dams.

Be it known that I William Eastby of the City of Washington District of Columbia have made a new and useful improvement in the construction of Coffre Dams called Eastby's Coffre Dams which is described as follows reference being had to the annexed drawings — This dam is constructed in the following manner. Wooden piles of a suitable length and strength are driven in by a pile driving machine in a circular form or many sided polygon inclosing the space where the ~~frame~~ or other work is to be built inside. These piles are shod at their points with iron or steel, and their heads protected by iron rings. When cut down to their proper height they are also tongued and grooved so as to fit into each other perfectly. In order to form the circle it will be necessary first to drive a pile near the center of the intended circle. Marked A. in the drawing. On this pile place a beam or boom B. turning on a collar by which the radius of the circle will be described. Piles C. will then be driven at about one foot within — the periphery of the beam and at about 8 feet asunder, another circle D. will be formed at the distance of about 10 feet outside of the first driving in piles in the same manner as the first. The heads of both circles will then be cut off at about 4 feet above high water at common tides. The frame being now prepared is ready to receive the pile driving engine. A circle E. similar to the upper one will be driven on the out side of the inner side of piles perpendicular

to parallel to the one above mentioned at low water marks. The piles being properly prepared with their edges converging to the center of the circle, the driving may be commenced. Care however must be taken that the first pile be driven perpendicular and secured to its place by treenails passing through its head and the upper rim. The next pile will be inserted into the groove of the first, driven home and secured. After the dam is enclosed the water may be pumped out to 10 ft below the surface, at which point a rib of oak 6. or from 6 to 12 inches thick may be secured on the inside of the dam or inner circle by large screw eye bolts H. after which the water may be pumped out to 10 feet and another rib I. inserted. The reason for placing these ribs as directed is not only to regulate the piles and strengthen the dam but in case any pile should be out of its place it can be brought into its place again by the screw bolts. Should any obstruction occur it will be necessary to be provided with a good oak pile having a steel shapet point with its head well hoisted. This pile is to be used to make way for the coffin dam or pile to be driven. When the bottom or foundation is good one tier of piles only is necessary. When two ranges of piles are deemed necessary, the space will be the same the loose mud must be taken from between the circles & the circles be secured by some bolts passing from the exterior circle to the interior circle to prevent them from being separated by the packing between them.

What I claim as my invention and desire to secure by Letters Patents is the peculiar construction of the before described Coffin dam, but I particularly claim the circular figure of the dam, whether a perfect circle, oval or a polygonal of many sides suspending with beams and giving it

Mr. B. greater strength
and principles. W. J. Clark
